G. A. VIEMEISTER.

SQUIRT CAN.

APPLICATION FILED DEC. 11, 1919.

1,372,053.

Patented Mar. 22, 1921.

Inventor,

George A. Viemeister
By A. D. Lewis, D. A. Lewis

ATTORNEY.

UNITED STATES PATENT OFFICE.

GEORGE A. VIEMEISTER, OF BROOKLYN, NEW YORK, ASSIGNOR OF ONE-FOURTH TO JAMES N. CATLOW, OF NEW YORK, N. Y., AND THREE-FOURTHS TO MINNIE VIEMEISTER, OF BROOKLYN, NEW YORK.

SQUIRT-CAN.

1,372,053.

Specification of Letters Patent.

Patented Mar. 22, 1921.

Application filed December 11, 1919. Serial No. 344,217.

To all whom it may concern:

Be it known that I, GEORGE A. VIEMEISTER, a citizen of the United States, residing in the borough of Brooklyn, county of 5 Kings, city and State of New York, have invented a certain new and useful Improvement 10 in Squirt-Cans, of which the following is a specification, reference being had to the accompanying drawings, which form a part of the same.

The object of my invention is to provide a device to be used in connection with or embodied in a squirt can which will catch oil or other liquid trickling down the outside of the spout, and return the same to the well, insuring at all times a dry well on the outside free from the liquid which has trickled down the outside of the spout.

The utility of this invention is apparent 20 inasmuch as it is of common knowledge that squirt cans often become greasy and leave tracks wherever they are stood. Unwittingly it often happens that a person will stand an oil can on a piece of cloth or other 25 commodity destroying the beauty of the same, and sometimes the utility thereof, by oil which has accumulated around the outside of the base of the well. It is the object of my invention to overcome this.

30 In the drawing which accompanies this specification and in which similar numerals apply to similar parts throughout,

The drawing is an elevation view of a portion of a squirt can having a part of the 35 spout broken away to show the working parts of my device.

Referring now in detail to the drawings, 1 represents a spout which may be made of any suitable construction or contour, and 2 40 represents the well of a squirt can.

I have shown the spout in two sections, the lower section of which is designated as 1^a. I have provided a basin 3 which preferably surrounds the spout 1, and the wall of 45 the spout constitutes one of the sides of said basin. This basin is provided with port holes 4 which communicate with a space leading into the well 2. A valve 5 is pro-

vided to control the ports 4 and is so fitted that when the can is not in use the ports 50 will be open and when the can is in use the ports will be closed. The valve is provided with ports 6 so as to constitute open communication between the basin 3 and the well 2 when the can is in non-use position. The 55 valve 5 is provided with a guide 7. This guide operates in an open sleeve 8 mounted in brackets 9 in the inner wall of the spout 1. These brackets are provided with openings 10 so as to permit the contents of the 60 can to pass the same.

At the end of the guide 7, I have provided a weight 11 which is made of sufficient diameter to rest upon the open sleeve 8 when the can is in non-use position.

65 A stop 12 preferably annular is provided to limit the downward travel of the valve 5.

It will be seen that, with my construction, upon the squirt can being tilted for the purpose of ejecting contents therefrom, the 70 valve 5 will slide forward so as to close the ports 4, of which there may be one or any desired number, and upon the can being placed in non-use position, the valve will fall back to the position shown in the drawings, opening the ports 4. Any liquid which 75 may trickle down the outside of the spout of the can will find its way into the basin 3 and be drained therefrom through the ports 4 and 6 into the well of the can.

80 The purpose of closing the ports 4 when the can is in use is to prevent liquid being passed through the spout from passing out through the ports 4.

I have illustrated and described what I 85 believe to be the best embodiment of my invention, but I do not desire to be limited to the forms illustrated, but what I desire to be protected in is set forth in the appended claims.

Claims:

1. In a squirt can, a nozzle, a basin connected thereto, drainage means for said basin, a sliding valve in said nozzle adapted to open and close said drainage means, a 95 stationary guide mounted in said nozzle, a

valve-guiding rod adapted to slide in said guide, said rod having connected thereto the aforesaid sliding valve.

2. In a squirt can, a nozzle, a basin connected thereto, drainage means for said basin, a sliding valve in said nozzle adapted to open and close said drainage means, a stationary guide mounted in said nozzle,

said guide being provided with a central sleeve, a valve-guiding rod adapted to slide in said sleeve, said rod being provided with the sliding valve at one end and a weight at the other end, said valve and weight being of greater diameters than the aforesaid sleeve.

GEORGE A. VIEMEISTER.
